UNITED STATES PATENT OFFICE.

NAPOLEON DU BRUL, OF CINCINNATI, OHIO.

CIGAR OR CIGARETTE WRAPPER CUTTING MACHINE.

SPECIFICATION forming part of Letters Patent No. 593,878, dated November 16, 1897.

Application filed April 8, 1897. Serial No. 631,284. (No model.)

To all whom it may concern:

Be it known that I, NAPOLEON DU BRUL, a citizen of the United States, and a resident of Cincinnati, in the county of Hamilton and State of Ohio, have invented certain new and useful Improvements in Cigar or Cigarette Wrapper Cutting Machines, whereof the following is a full, clear, and exact specification.

My present invention relates to machines which employ a hollow cutting-die over which the tobacco-leaf is placed and upon which it is held smoothly by means of atmospheric pressure induced by exhausting the air from beneath some or all of the leaf's area outside of the cutting-die and a suitable pressure device which bears above the leaf upon the edge of the cutting-die, while one of said parts moves relatively to the other and effects the cutting action.

My present invention consists in novel features of construction in such a machine whereby it is better adapted to perform the several functions of such a machine as well as to perform new functions not heretofore attainable with machines of this class as formerly constructed and whereby the construction of the machine as a whole is improved, as herein-after described and claimed.

My invention will be fully understood upon reference to the accompanying drawings, in which—

Figure 1 is a side elevation of my improved machine. Fig. 1^a is a detail vertical transverse section showing a view, on an enlarged scale, of a part of the head of the arm shown in Fig. 1. Fig. 1^b is a side elevation showing a detail view of a slightly rounding or tapering roller wherein the curvature of the periphery is slightly exaggerated for the purpose of illustration. Fig. 2 is a front elevation. Fig. 3 is a rear elevation. Fig. 4 is a top plan. Fig. 5 is a central vertical section from front to rear through the table, suction-chamber, cutting-die, and device for applying cutting pressure to said die.

1 represents the legs or frame, which may be of any suitable construction, but which I prefer to provide with front brackets 2 to support a trough 3 for scraps of leaf and with rear brackets 4 to support an air-trunk 5, which has to do with the suction apparatus to be hereinafter described. The frame may

also be provided with a horizontal lateral shelf 6 to hold material from which the wrappers are to be cut, or for other convenient purpose, and an inclined lateral shelf 7, upon which to place a cigar-mold containing the fillers which are to be wrapped. 8 represents the table, and 9 is a shelf supported by brackets 10; but these features may be varied at will without departing from my present invention.

11 represents the removable platen, which surmounts and covers a suction-chamber 12, mounted upon the table 8, and 13 is a removable hollow open cutting-die mounted on the table within the suction-chamber, so that the latter surrounds it and protruding slightly through the platen, so that the leaf may be cut upon it.

14 is an oscillating arm pivoted in any suitable manner upon the table—as, for instance, between set-screws 15 and 16 in the upper and lower ends of a standard 17, which is secured to the table.

18 is a pressure device of improved novel construction to be presently described, and 19 is the customary handle, by which the arm 14 may be moved when it is desired to effect this by hand.

According to one of the features of my present invention I make the cutting-die 13 hollow and open at the top—that is to say, without a supporting block or filling—the object of this being to provide a well or pocket into which the wrappers may drop or be forced as they are cut. I thus provide for cutting in rapid succession and collecting a number of wrappers, which may afterward be successively withdrawn and utilized in the usual manner or removed in bulk to any place of use. In order to avoid creating a vacuum in the cutting-die, I maintain it in communication with the outer atmosphere by making one or more openings—such, for instance, as 21—in the bottom of the well of the cutting-die, which admits normal atmospheric pressure to said cutting-die at all times and avoids the development of vacuum in the latter, which might occur and cause the leaf to sag and interfere with the smoothness of the cut. The opening 21 or such other openings as may be employed are of sufficient width to avoid stoppage of the air by the

wrappers as they accumulate within the cutting-die.

There are several other advantages in employing the kind of die described. For instance, it avoids the drying out of the tobacco wrapper by the air-suction, which is very desirable in the manufacture of certain classes of cigars.

A further advantage is that it permits the work to be classified—that is to say, it provides for employing cheap labor to cut out the wrappers, while the time of the skilled labor need only be employed in applying the wrappers.

15 A further feature of my present invention relates to means for holding the tobacco-leaf during the cutting operation, for which purpose I provide perforations 22 in the removable platen 11 outside of the cutting-die, and thus obtain ample holding force to insure the smooth and accurate cutting of the wrapper.

As shown in Figs. 1, 2, and 5, a pipe 23 connects the suction-chamber 12 with the air-trunk 5. Any other suitable connections for developing pressure in the chamber 12 may, however, be employed.

The pressure device 18 comprises two independently-mounted parallel rollers 24 and 25, bearing upon the respective sides of the cutting edge of the cutting-die and made independently yielding in a vertical direction to cause them to press uniformly on every point of the cutting edges as they pass over the leaf, and thus insure perfect cutting. The rollers also overlap each other in such a manner as to fully cover those parts of the edges which extend more or less in a direction transverse to the travel of the rollers. Each roller may be made slightly rounding or tapering, as shown at 25^a in Fig. 1^b, in order to avoid contact with the leaf except at the point of cutting. The manner of mounting the rollers will be understood upon reference to Fig. 1^a, wherein 26 represents a box which receives the spindle 27 of a hanger 28, and in said hanger is mounted the journal 29, upon which the roller is fixed by adjustable collars 30. (See Fig. 5.) The spindle 27 has a reduced portion 31, surrounded by a spring 32, which is confined between the upper end of the bore in the box and the shoulder 33, formed on the spindle. Upon its upper end the spindle is threaded to receive jam-nuts 34, by which the roller-mounting may be adjusted to different heights. Aside from the advantages named as incident to these rollers it is obvious that they can be moved longitudinally upon their axes after they have become indented from wear and can be interchanged, so as to bring new surfaces into play, or when worn to a great extent a roller can be replaced at small cost. While I have shown this form of pressure device mounted upon a swinging arm, it is quite obvious that it could be mounted upon a reciprocating carrier, which slides from side to side, or the same effect could be produced and many of the

advantages attained by having the pressure device fixed and making the cutting-die with its surrounding parts slide relatively beneath the rollers.

To operate the swinging arm 14 or any other form of carrier which may be employed to carry the rollers, said carrier is provided with an arm 35, (see Fig. 5,) which is connected by links or equivalent connections 36 (see Fig. 3) with the upper ends of a pair of bell-crank levers 37 and 38, fulcrumed, respectively, at 39 and 40 and having their horizontal arms connected by rods or equivalent connections 41 with pedals 42 and 43. The carrier or arm 14 may thus be reciprocated from side to side by pressing the pedals alternately.

While I have described the open die in which the wrappers are accumulated as they are cut, it is obvious that the remaining features of my present invention are by no means restricted to use in combination with a cutting-die of this character, but are applicable to machines in which any form of cutting-die is employed.

The platen 11 is secured by screws to the suction-chamber, so as to be removable, which is of great advantage, as it provides simple means whereby the changing of the cutting-die and surrounding platen is readily accomplished.

Having thus described my invention, the following is what I claim as new therein and desire to secure by Letters Patent:

1. A cigar or cigarette wrapper cutting machine comprising a table having independent air and suction openings, a hollow open cutting-die surrounding said air-opening and providing a wrapper-receptacle thereover, the suction-chamber surrounding said cutting-die and said suction-opening, and the platen having an opening through which the cutting-die projects, provided with perforations surrounding the cutting-die and forming the top of the suction-chamber; substantially as described.

2. A cigar or cigarette wrapper cutting machine comprising a table having independent air and suction openings, a removable hollow open cutting-die surrounding said air-opening and providing a wrapper-receptacle thereover, the suction-chamber surrounding said cutting-die and said suction-opening and the platen having an opening through which the cutting-die projects and provided with perforations surrounding the cutting-die and forming a removable top to the suction-chamber; substantially as described.

3. The combination with the cutting-die of a wrapper-cutting machine and a roller-support; of a pair of rollers having their axes mounted in the same horizontal plane approximately, in parallel position approximately, overlapping at their inner ends, and adapted to work on opposite sides of the cutting-die to insure the perfect cutting of the wrappers; substantially as described.

4. The combination with the cutting-die of a wrapper-cutting machine and a roller-support; of a pair of rollers having their axes mounted in the same horizontal plane approximately, in parallel position approximately, adjustable transversely of the cutting-die, overlapping at their ends, and adapted to work on opposite sides of the cutting-die to insure the perfect cutting of the wrappers; substantially as described.

5. The combination with the cutting-die of a wrapper-cutting machine; of a roller-support comprising an oscillating arm having a

box formed with bores in different vertical planes, the spring-hangers having spindles 15 adjustably mounted in the bores of the boxes, and the pair of horizontal and parallel overlapping rollers mounted in the hangers and adapted to work on opposite sides of the cutting-die to insure the perfect cutting of the 20 wrappers; substantially as described.

NAPOLEON DU BRUL.

In presence of—

H. WHYRICH,
E. F. DU BRUL.
